(57) **CLAIM**

The ornamental design for a display screen with animated graphical user interface for vehicles, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image in a sequence of a display screen with an animated graphical user interface for vehicles;

FIG. 2 is a front view of a second image thereof;

FIG. 3 is a left view thereof;

FIG. 4 is a top view thereof; and,

FIG. 5 is a front view thereof in a state of use.

The broken lines seen in FIGS. 3 and 4 illustrate portions of the display screen and form no part of the claimed design. The broken lines seen in FIG. 5 illustrate environment and form no part of the claimed design.

The right view is omitted because it is a mirror image of the left view. The bottom view is omitted because it is a mirror image of the top view. The appearance of the image sequentially transitions between the images shown in FIG. 1 and FIG. 2. The process or period in which one image transitions to another image forms no part of the claimed design.
